No. 36,406.

Patented June 30, 1903.

UNITED STATES PATENT OFFICE.

HERMAN IHLENBURG, OF PHILADELPHIA, PENNSYLVANIA, ASSIGNOR TO THE AMERICAN TYPE FOUNDER'S COMPANY, OF NEWARK, NEW JERSEY, A CORPORATION OF NEW JERSEY.

DESIGN FOR A FONT OF TYPE.

SPECIFICATION forming part of Design No. 36,406, dated June 30, 1903.

Application filed April 27, 1900. Serial No. 14,634. Term of patent 14 years.

To all whom it may concern:

Be it known that I, HERMAN IHLENBURG, a citizen of the United States, residing at Philadelphia, Pennsylvania, have invented a new, original, and ornamental Design for a Font of Type, which is fully shown in the accompanying typographical impression, to which reference is made.

I claim as my invention—
10 The ornamental design for a font of type, substantially as shown in the accompanying typographical impression.

In testimony whereof I have signed my name to this specification in the presence of two subscribing witnesses.

HERMAN IHLENBURG.

Witnesses:
